[57] CLAIM

The ornamental design for an ant stopper for use with a
hummingbird feeder, as shown and described.

DESCRIPTION

FIG. 1 is a perspective view of the ant stopper for use
with a hummingbird feeder showing my new design;
FIG. 2 is a side elevational view thereof, the side oppo-
site being a mirror image of the side shown;

FIG. 3 is a front elevational view thereof, the rear view
being a mirror image of the front shown;

FIG. 4 is a top plan view thereof; and,
FIG. 5 is a bottom view thereof.

FIG.1.

FIG. 3.

FIG. 2.

FIG. 5.

FIG. 4.
